COMBUSTION APPARATUS

Lawrence W. Corbett, Belmont, Mass.

Application January 26, 1932, Serial No. 538,882

2 Claims. (Cl. 110—36)

This invention relates to combustion apparatus and to a method of combustion.

One object of the invention is to provide a novel and improved combustion apparatus particularly designed for use in heating dwelling houses and for similar heating purposes where it is desired to burn solid fuel in an automatic manner.

Another object of the invention is to provide a novel method of combustion involving the control of the thickness of the fuel bed in a novel, economical and highly efficient manner.

With these general objects in view and such others as may hereinafter appear, the invention consists in the heating apparatus and in the method of combustion, and in the various structures, arrangements and combinations of parts hereinafter described and particularly defined in the claims at the end of this specification.

In the drawings illustrating the preferred embodiment of the invention, Fig. 1 is a vertical sectional view of the improved heating apparatus; Figs. 2 and 3 are sectional diagrammatic views illustrating portions of the heating apparatus under different conditions of operation; and Fig. 4 is a side elevation of the lower portion of the machine illustrating the mechanism for operating the grate.

The present invention contemplates a construction of heating apparatus which is designed to enable the commercial solid fuels now upon the market such as the commercial grades of anthracite and coke to be burned in a manner which is automatic for substantial lengths of time, as for example a week, thereby reducing to a minimum the attention required and enabling the dwelling house to be heated in a satisfactory, safe and economical manner. In the preferred embodiment of the invention the combustion or heating apparatus is provided with a conical grate supported for rotation within a combustion chamber, and provision is made for feeding the fuel from a supply hopper preferably on the overfeed principle to the upper portion of the grate. Air for supporting combustion is supplied through the grate and through the fuel bed, and provision is made for automatically moving the grate so that during continued combustion and in the operation of the apparatus, the fuel gradually traverses down the grate to be discharged as ash over the periphery or base thereof. In order to adapt the apparatus for most efficient and successful operation upon fuels of various size, the apparatus is preferably provided with a removable fuel discharge tube, arranged to project into the combustion chamber, and the lower end of

which is arranged to terminate a predetermined and short distance above the conical grate. I have found that for most efficient and successful operation of the combustion apparatus, it is desirable to vary the length and sectional size of the fuel discharge tube, and in the preferred embodiment of the invention the fuel discharge tube is removably supported within the hopper to facilitate the substitution of different sizes of fuel tubes when the apparatus is to be operated upon fuel of different size.

Referring now to the drawings illustrating the preferred embodiment of the invention, 10 represents a combustion chamber, 12 a conical grate, 14 a supply hopper for retaining the supply of the solid fuel and from which the coal may be discharged onto the grate through a discharge tube 16. Provision is made, as will be described, for rotating the grate and for supplying the primary air through the grate for maintaining combustion, and during the operation of the apparatus a conical incandescent bed of fuel is maintained upon the grate in an automatic manner so long as a supply of fuel is maintained within the supply hopper 14. I have found that most successful and efficient operation of the apparatus depends to some extent upon the relation between the size of the discharge tube 16 and the distance of the end of the tube from the upper portion of the conical grate, and I have found it desirable to vary the distance from the end of the discharge tube 16 to the top of the grate in proportion to the size of the lumps of particles of the fuel, it being understood that the larger the pieces of fuel, the greater the distance in order to maintain a given output from the apparatus. It has been found that the rate of combustion is proportional to the size of the pieces of the fuel, and that the larger the individual pieces, the longer time is required for burning, and consequently with the larger sizes of fuel a thicker fuel bed is needed than with the smaller sizes. In the illustrated apparatus the flow or discharge of the fuel from the hopper through the discharge tube 16 is controlled by the fuel bed itself, and in order to provide a thicker fire, the sectional size of the coal tube should be varied when it is desired to use different sizes of fuel. In the illustrated apparatus the discharge tube 16 is provided with a flange 21 designed to rest upon an annular shoulder 23 surrounding the opening 25 in the bottom of the hopper, so that when it is desired to alter the thickness of the fuel bed or the distance from the end of the discharge tube to the conical grate, these results may be conveniently accomplished

by the substitution of a different and correctly proportioned fuel discharge tube 16. It is preferred to construct the conical grate of a plurality of sections 26 which interlock to rotate as a unit, 5 and the lower section 30 is preferably cast to provide a skirt 32, the upper surface of which is preferably substantially horizontal and of a sufficient length so that the skirt projects outwardly a substantial distance beyond the inner wall of the lower 10 portion of the combustion chamber. The lower portion of the inner wall is provided with ribs 35 for cooperation with the rotary grate in grinding ash and such clinker as may be formed. The upper surface of the skirt 32 is spaced from the 15 lower portion of the inner wall of the combustion chamber to form a throat or constricted passage indicated at 38.

The conical grate 12 is, as herein shown, made up of a plurality of sections, and each section is 20 provided with depending lugs 47 which cooperate with recesses in the next succeeding section to lock the sections together and to space one section a short distance from the next lower section so as to provide a series of downwardly and outwardly 25 extending air channels 49 through which the primary air may be caused to pass through the fuel bed supported upon the grate. The lower section of the grate is bolted or otherwise secured to a ring 43 having a ring gear 44 cooperating with a 30 driving pinion 45 secured upon the end of a drive shaft 46 rotated through suitable mechanism, as will be described. The grate is supported on a series of ball-bearings 50 within a raceway formed by cooperative surfaces 57, 58 of portions of the 35 lower section of the grate and ring 43 respectively, and the remaining sides of the raceway are formed by an angular recess in a supporting ring 59 mounted upon the frame, as shown. The skirt 32 projecting from the lower section of the grate 40 is provided with a downwardly turned lip 60 extended over the supporting ring 59 illustrated in detail in Fig. 3 to thereby assist in protecting the bearings against the entrance of ash and dirt.

The conical grate 12 is hollow, and as herein 45 shown, cooperates with the bottom wall 64 of the burner pot to form a closed chamber 66 to which air is admitted under pressure through an air inlet pipe 65 from any convenient source of supply, as for example a blower or fan, not shown. During 50 the operation of the apparatus the air under pressure from within the closed air chamber 66 passes through the narrow air passages 49 between successive sections of the grate to supply air for the combustion of the fuel. The construction of air 55 pressure chamber 66 formed within the grate and burner pot serves to assist in preventing the entrance of ash or dirt into the bearings 50 by reason of the pressure through the bearings and outwardly under the projecting skirt.

During the operation of the apparatus, provision is made for rotating the grate, and as herein shown, the driving shaft 46 upon which the driving gear 45 is mounted, has affixed to its outer end a ratchet 70 with which a pawl 72 cooperates to advance the ratchet and consequently to effect rotation of the conical grate when the pawl is advanced. The pawl is carried upon the top of a pawl arm 74, as best shown in Fig. 4, which is connected to an arm 76, the latter being connected by a link 78 to a crank 80. The crank 80 is arranged to be revolved from an electric motor 82 through the medium of a reduction gearing 84 of any usual or preferred form now upon the market. Provision is made for controlling the 60 effective throw of the pawl 72 to control the ex-

tent of grate movement at each revolution of the crank 80, and as herein shown, a shield member 84 pivoted upon the shaft 46 is arranged to be moved relative to the pawl so as to slide under a pin projecting from the pawl to maintain the nose of the pawl disengaged from the teeth of the ratchet for the desired portion of the normal stroke of the pawl to thereby prevent it from picking up any desired number of teeth. The pivoted shield is preferably connected to a control link 85 running from a thermostat or from a manual control.

In order to supply fuel to the conical grate to maintain a substantially uniform bed of fuel thereon, as herein shown, a bulk supply of fuel is stored within a fuel reservoir 14 located above the grate in a position from which the fuel may automatically flow onto the grate by gravity. The flow of the fuel is controlled by the rate of consumption of the fuel bed in cooperation with the ash discharged therefrom and as long as fuel remains in the hopper a substantially uniform fuel bed is maintained upon the grate. During the combustion sufficient air is supplied through the fuel bed to maintain practically the entire 100 length of fuel bed incandescent, and the ash resulting from the combustion gradually slides and works downwardly toward the restricted throat or passage between the skirt 32 and the dead ring 34 preparatory to being forced over the skirt 105 to drop into the ash-pit where it may conveniently be caught in a removable ash receptacle 92.

Provision is also preferably made for effecting relative displacement or movement of the upper grate section 27 with relation to the remainder of the grate, and for this purpose the upper section 27 of the grate is mounted independently of the remainder of the grates upon the upper end of a post 75 affixed to the burner pot so as to permit the upper grate section to rotate about the axis of 110 the post 75. The next lower of the grate sections 26 is provided with a slot 73 of the shape illustrated and within which a pin 80 depending from the upper grate section 27 is adapted to ride, so that during the rotary movement of the 115 main body of the grate about its own axis, the upper grate section 27 is moved by the engagement of the walls of the slot 73 with the pin 80. The post 75 is mounted at one side of the axis of the conical grate, and with this construction, as 120 125 the conical grate is rotated through the driving mechanism previously described, the upper grate section is caused to be displaced with relation to the main body of the rotating grate.

In Figs. 2 and 3 I have illustrated diagrammatically the differences in the sectional size of the fuel discharge tube 16 and also in the distance at which the tube is arranged to terminate in order to enable the thickness of the fuel bed to be controlled and varied in order that the apparatus 130 may operate with maximum efficiency. As above stated, during the operation of the apparatus, fuel is fed through the discharge tube 16 onto the top of the conical grate and the latter is slowly rotated during combustion to effect the 135 gradual movement of the burning fuel bed down the grate. The ash is discharged from the base of the grate substantially as fast as it accumulates in the lower portion of the fuel bed, and in accordance with the present method either the sides 140 of the fuel discharge tube 16 or the distance of the tube from the top of the fuel bed, or both, may be varied to insure the maintenance of a predetermined thickness of fuel bed depending upon the size of the fuel in order that the apparatus 145 150

- may operate with maximum efficiency to maintain a substantially incandescent cone of fuel upon the grate at all times during combustion except during bank fire periods.
- 5 While the preferred embodiment of the invention has been herein illustrated and described, it will be understood that the invention may be embodied in other forms within the scope of the following claims.
- 10 Having thus described the invention, what is claimed is:—
1. A combustion apparatus for effecting substantially complete combustion of solid fuel such as coal having, in combination, a combustion chamber, a conical grate rotatably supported within the chamber provided with openings therein of such character as to permit the passage of air therethrough and to prevent the passage of ash therethrough, fuel supply means including a hopper for containing a bulk supply of the fuel positioned immediately above the grate provided with a downwardly inclined bottom having an opening positioned above the apex of the grate and a fuel discharge tube extending downwardly from the bottom of the hopper to within a short distance of the top of the grate, said fuel discharge tube being supported at its upper end upon the walls of the hopper surrounding said opening therein and capable of being removed by bodily movement upwardly through said hopper whereby to enable fuel discharge tubes of different diameter and length to be conveniently installed, means for passing sufficient air under pressure through the conical fuel bed supported upon the grate to effect substantially complete combustion of the fuel, and power operated means for continuously and slowly rotating the grate during combustion periods to remove ash from the lower portion of the fuel bed substantially as fast as it accumulates therein whereby in cooperation with the agitating effect induced in the upper portion of the fuel bed by the engagement therewith of the fuel discharge tube, the fuel bed is progressively caused to pass down the grate and during the entire combustion period is continuously and automatically maintained at incandescence.
2. A combustion apparatus for effecting substantially complete combustion of solid fuel such as coal having, in combination, a combustion chamber, a conical grate rotatably supported within the chamber provided with openings therein of such character as to permit the passage of air therethrough and to prevent the passage of ash therethrough, fuel supply means including a fuel discharge tube extending downwardly to near the apex of the grate in a position to engage the fuel bed thereon, and means for supporting the fuel discharge tube to permit replacement thereof without dismantling the apparatus, means for passing sufficient air under pressure through the conical fuel bed supported upon the grate to effect substantially complete combustion of the fuel, and power operated means for continuously and slowly rotating the grate during combustion periods to remove ash from the lower portion of the fuel bed substantially as fast as it accumulates therein whereby in cooperation with the agitating effect induced in the upper portion of the fuel bed by the engagement therewith of the fuel discharge tube, the fuel bed is progressively caused to pass down the grate and during the entire combustion period is continuously and automatically maintained at incandescence.
